UNITED STATES PATENT OFFICE.

JOSEPH P. WOODS, OF WASHINGTON, DISTRICT OF COLUMBIA.

STATISTICAL COMPILATION DEVICE.

Application filed October 7, 1924. Serial No. 742,260.

To all whom it may concern:

Be it known that I, JOSEPH P. Woods, a citizen of the United States, residing in Washington, in the District of Columbia, **5** have invented new and useful Improvements in Statistical Compilation Devices, of which the following is a specification.

My invention has reference, in its broad aspect, to improvements in devices for use **10** in conjunction with suitable perforating, assorting and distributing machinery for the purpose of facilitating the classification of statistical data such as is commonly required in the compilation of directories of **15** all kinds, pay rolls, tax, voters and mailing lists, army rosters, and the like; and more particularly it is my purpose to improve upon and greatly increase the adaptability of the similar means defined with particularity in my previous Patent #1,343,755 **20** granted June 15th, 1920.

Heretofore the cards, slips or sheets employed to receive perforations indicative of the data to be classified have been found to **25** be exceedingly restricted in the character of their make-up, such for instance as in the number of characters thereon displayed and in the number of fields, thereby placing a decided limit upon their use. My present **30** card, slip or sheet as distinguished from those above defined contemplates, among other things, the utilization of means in the form of multiple designating perforations and a unique arrangement of characters, **35** symbols, letters, numerals, fields and the like, for greatly increasing the amount of data which may be placed upon a card. Furthermore, not only is my present card adapted for use in conjunction with assorting and distributing machinery for the compilation of statistical data, but it may be employed with equal facility in the automatic operation of any key board controlled machine of the type exemplified by a supplementary key board controlling device for **40** translating the significance of the perforations in the punched cards to be conventional manipulation of the keys thereby permitting of the automatic operation through **45** the instrumentality of my present cards of

typewriters, linotype, and monotype machines and the like.

More particularly, it is an essential object of my invention to simplify the devices now in use by consolidating in units certain groups of characters, letters, symbols, numerals, and the like, such for instance, as the letters of the alphabet and a number of common abbreviations, and then accomplishing the general designation of that unit by a designating perforation, and the particular segregation of a character in that unit by another perforation. The key board for a punching device adapted for use with my invention is thereby greatly simplified **55** for it is necessary to have but one key for each of my several vertical and horizontal delineated fields, each field being a unit as above defined, while the range of adaptability of the card, sheet or slip is greatly increased. **60**

The structural elements and other means employed to accomplish the above and other equally important objects and advantages will be hereinafter more fully described in **65** detail and specifically pointed out in the claims appended hereunto and forming a part of this specification, but the scope of the invention may only be determined by the limits defined in the claims. **70**

In the accompanying drawing, wherein is illustrated the preferred embodiments of **75** my invention:—

Figure 1 is a view of an arrangement of my card adapted to receive such data as is usually required in the compilation of city **80** directories, etc., and bearing in the left hand columns numerals designed to identify by code certain common names such as Smith, Jones, Brown, or the like.

Figure 2 is a view of an arrangement of my card adapted for the purpose of city **85** directories and the like and showing the manner of perforating the same to correspond with the person, business and address specified.

Figure 3 is a view of several modified forms of my arrangement of characters, and is especially adapted for the compilation of **90** directories,

Figure 4 is a view of the key board of a punching machine adapted for use with my card.

In the drawings like characters of reference designate like or similar parts throughout the several views, in which;

The numeral (1) designates a card bearing 45 vertical delineated columns (2) which are identified by reference numerals 10 (3) and notches (4), the purpose of which is to facilitate the use of my card in the manipulation of key board controlled machines such as typewriters, linotypes and monotype machines or the like. The card is 15 further divided into preferably 12 horizontal delineated columns or fields (5), the lower nine of which are designated by reference numerals (6) and the upper three by designating characters X1—X2 and 0, or 20 the cipher column. The card is also preferably divided, in some instances, into vertical heavy line delineations (7) representing sections corresponding to data to be compiled.

25 In the form of my card shown in Figure 1 the twenty-six letters of the alphabet and the two abbreviations Mc. and St. are arranged in four groups which are vertically consecutive and arranged in fields defined 30 by vertical delineations as shown, there is also a fifth column including any desired and commonly used symbols. In the three remaining vertical left hand fields are numerals from one to nine so that data covering 35 digits of three places can be punched. This numeral unit may be, and preferably is used for the purpose of coding certain common names as Smith, Jones, Brown or the like or to indicate long names for which 40 abbreviation is necessary for proper designation on the card. The numerals 1 to 9 also designate the horizontal fields. As indicated, when read horizontally the alphabet and symbols of the five fields are arranged in 45 units as follows: AHNT (symbol), BIOU (symbol), CJPV (symbol), DKQW (symbol), ELRX (symbol), F Mc. St. Y (symbol), and GMSZ (symbol); there are seven such units and they are arranged in the 50 horizontal fields identified by the numerals 3 to 9. Above the units are horizontal fields identified by X1—X2—0—1 and 2; the 0 (or cipher) field being used as a check to show that a column has not been missed or 55 the like. Manifestly then if punches can be made in the card to designate the unit and the particular letter or symbol in the unit complete words can be spelled out or street addresses or the like. This is the end I 60 desire to accomplish in the most simple manner possible.

I utilize one key in the key board of a suitable punching machine for each of the five vertical delineated columns of letters 65 and symbols, and one key for each of the

seven horizontal delineated columns of letters and symbols. The five keys for the vertical columns bear the following indicia 0—space—0, X1—HIJKLMc M; X2—NOPQRStS; 1—TUVWXYZ; and 2—the symbols; the seven keys designating the horizontal fields bear the letters and symbol of each of the units. The last mentioned keys I term "designating" keys, and the first are those to particularly specify the unit to be punched. Consequently by punching in a certain unit any one of the five indicia may be indicated, and then at the same time manipulating the designating key to specify the character in that unit. The proper letter or symbol is absolutely segregated.

In Figure 2 is shown a complete name, business the code number of which is 62 and address. The first letter of the name is S, therefore key 9 bearing the letters GMSZ and symbol is manipulated showing that the desired letter is in that unit, and at the same time the particular letter is designated by manipulating key X2—bearing the letters NOPQRStS, but the X2 key will punch two horizontal delineated spaces from the top, and the 9 key, will designate the unit. Manifestly therefore the letter S will be segregated. The remaining letters are indicated in the same manner, i. e. by manipulating the desired keys. There is no designating key for field ABCDEFG.

By this type of card I am enabled to utilize 35 letters and symbols which is considerably more than have heretofore been found practical. Furthermore, this large number of letters and symbols are indicated on my card by the manipulation of but twelve keys. I have found that rapid, accurate and efficient compilation and classification of data can be obtained by my unique method.

In Figure 3 is shown a card delineated in the same manner as the card shown in Figure 1, but having heavy line delineations (7) between which are arranged slightly modified forms of my method of compilation. This card is particularly adapted for use in compiling the data required for city directories. The first section A is made up in accordance with the preferred embodiment of my invention as hereinbefore described with reference to Figures 1 and 2; but section B shows but four fields in each unit (horizontal) and eight fields in the vertical columns. However by the method exemplified by section B but 32 characters can be utilized; and in section C wherein three fields are comprised in each unit (horizontal) and nine in the vertical columns but 27 characters are practicable. Section D represents the method employed in my prior Patent #1,343,755 granted June 15th 1920,

and by comparison of this section with the others the difference can be readily seen. The designating punches in each of the above cases varies in the manner shown clearly in 5 the drawing.

While it is believed that the operation of my device is manifest in the foregoing description it is desired to particularly emphasize the fact that while I have described 10 my designating fields as at the top of the card, they may be placed also at the bottom, in which case the cards are run through the assorting machine in reverse order.

While in the foregoing, there has been 15 illustrated and described such combination and arrangement of elements as constitute the preferred embodiments of my invention, it is nevertheless desired to emphasize the fact that interpretation of the invention 20 should only be conclusive when made in the light of the subjoined claims.

I claim:-

1. A card device for use in mechanically manipulating the key boards of key board 25 controlled devices such as linotypes and the like, comprising doubly aligned characters, delineated fields indicative of the groups of characters in one direction of alignment and adapted to receive therein perforations or 30 indentations designating any one of the respective groups, and delineated fields indicative of the groups of characters in another direction of alignment and adapted to receive therein perforations or indentations 35 designating with particularity any one of the characters in the first mentioned groups.

2. A card device for use in mechanically manipulating the key boards of key board 40 controlled devices such as linotypes and the like, comprising plurally aligned characters arranged consecutively in one direction of alignment only, delineated fields indicative of the groups of characters in one direction 45 of alignment and adapted to receive therein indicia designating any one of the respective groups, and delineated fields indicative of the groups of characters in another direction of alignment and adapted to receive therein 50 indicia designating with particularity any one of the characters in the first mentioned groups.

3. A card device comprising a predetermined number of different characters arranged in vertically and horizontally aligned groups, horizontally delineated fields each indicative of the respective groups of characters in horizontal alignment and adapted to receive therein indicia designating 55 any one of the groups, other horizontally aligned fields representative of the number of characters in the horizontally aligned groups, and vertically delineated fields indicative of the respective groups of characters in vertical alignment and adapted to 60

receive therein indicia designating with particularity any one of the characters in any designated group.

4. A card device comprising a predetermined number of different characters arranged in vertically and horizontally aligned groups, horizontally delineated fields each indicative of one of the respective groups of characters in horizontal alignment and adapted to receive therein perforations or 70 indentations designating any one of the groups, vertically delineated fields indicative of the respective groups of characters in vertical alignment and adapted to receive therein perforations or indentations designating with particularity any one of the characters in any designated group, and marginal fields adapted to be indented to designate with particularity certain predetermined portions of the data exemplified 75 by the respective designated fields.

5. A card device comprising a predetermined number of different characters arranged in vertically and horizontally aligned groups, horizontally delineated fields each indicative of one of the respective groups of characters in horizontal alignment and adapted to receive therein perforations or 80 indentations designating any one group, vertically delineated fields indicative of the respective groups of characters in vertical alignment and adapted to receive at a point removed from the punch or perforation 85 designating the group of characters in horizontal alignment another punch or perforation designating with particularity any one of the characters in that group, and marginal fields adapted to be indented to designate with particularity certain predetermined portions of the data exemplified by 90 the respective designated fields.

6. A card or sheet of the type defined comprising plurally aligned characters forming groups in each direction of alignment, delineated fields indicative of the respective groups of characters in alignment in one direction, other delineated fields indicative of the respective groups of characters in alignment in another direction, and the characters comprising the groups in each direction of alignment constituting a key 100 for the keys of the key board of a punching machine whereby perforations may be made in one delineated field to designate a particular group, and in the other delineated fields 105 to designate with particularity a character of that group.

7. A card or sheet of the type defined comprising a plurality of groups of characters, delineated fields indicative of the respective groups and adapted to receive therein perforations or indentations designating any one of the groups, and other delineated fields indicative of the respective characters and adapted to receive therein 110

perforations or indentations designating certain of the respective groups, and another ¹⁰ with particularity a certain character in any of the delineated fields adapted to receive one of the groups.

8. A card or sheet of the type defined comprising plural groups of characters, and ⁵ plural groups of delineated fields corresponding to the groups of characters, one of the delineated fields adapted to receive perforations or indentations designating certain of the respective groups, and another ¹⁰ with particularity any one of the characters in the groups.

In testimony whereof I affix my signature hereunto.

JOSEPH P. WOODS.
